TELEPHONE SYSTEM

Roswell H. Herrick, Oak Park, Ill., assignor to
 Associated Electric Laboratories, Inc., Chicago,
 Ill., a corporation of Delaware

Application February 24, 1939, Serial No. 258,264

30 Claims. (Cl. 179—18)

The present invention relates to improvements in telephone apparatus of the general character disclosed and claimed in applicant's copending application Serial No. 207,433, filed May 12, 1938, now Patent No. 2,187,902, granted Jan. 23, 1940. More particularly, this invention relates to improved telephone apparatus for providing simplified and more direct calling facilities between the telephone substation of an important executive or official and the telephone substations of subordinates who are frequently called from the executive telephone substation.

As explained in the above referred to patent, it sometimes occurs that one party located at a given substation may have occasion to call the telephones of a particular group of other parties at frequent intervals. This is particularly true of an executive who relies upon telephone facilities to secure information from his immediate subordinates. In a situation of this character, the delay incident to the operation of a manual system or the labor incident to the operation of the calling device in automatic systems may prove burdensome to the party initiating the calls. In order to simplify the calling operation, the improved direct call system disclosed in the above-mentioned copending application was developed. This system is so arranged that calls to a number of telephones may be initiated at the special substation either by using a conventional dial operated calling device or by the simple expedient of selectively actuating calling keys individually corresponding to the telephones which are frequently called. In the disclosed arrangement, there is provided an automatic telephone system including an exchange at which the plurality of lines of the system terminate. One of the lines of the system extends to a special or executive substation of the character mentioned above. Automatic switching equipment of the impulse responsive type is provided in the exchange for establishing connections between the lines extending to the exchange, the arrangement being such that the automatic switching equipment is controllable from the executive substation or by way of any of the lines extending to the exchange, to establish communication connections between the executive substation and the lines. There is also provided, in the exchange, special automatic switching means having access only to the group of subordinate lines to which calls are frequently initiated at the executive substation. This special automatic switching means is individual to the executive substation and is controllable

only from this substation to establish a second communication connection between the substation and a second of the lines extending to the exchange. This second communication connection may be set up in the absence of a connection of the first type as mentioned above, or may be set up while a connection of the first type exists and without releasing the same. More specifically, there is provided, at the executive substation, a plurality of key operated calling switches which individually correspond to the subordinate lines forming the group accessible to the automatic switching means mentioned above, and control apparatus operative in response to the operation of any one of the calling switches for causing the special switching means to extend a connection from the executive substation to the particular one of the subordinate lines corresponding to the operated calling switch. For the purpose of communicating over a connection of the first type, there is provided, at the special or executive substation, the usual transmitter and receiver preferably arranged in the form of the handset, which two elements are normally connected and arranged to be used in conversing over a connection of the first type. Auxiliary transmitting and receiving means are also provided at the special substation which are normally connected and arranged to be used in communicating over a connection of the second type. Switching apparatus is provided for operatively connecting the auxiliary transmitting and receiving means to be used in communicating over either of the two types of connections briefly described above. More particularly, a pair of relays are provided which are under the control of manually operable answer and transfer switches located at the substation and are operative selectively to connect the auxiliary transmitting and receiving means to be used in communicating over an established connection of either type. The arrangement is such that the two relays are jointly operative to transfer the auxiliary transmitting and receiving means from a connection of one type to a connection of the other type. The answer switch includes contacts for completing the operating circuits of both relays, and the transfer switch includes contacts for interrupting the operating circuit of the transfer relay without deenergizing the other relay, thus providing an arrangement wherein the desired transfer of the auxiliary transmitting and receiving means may be effected by selective operation of the answer and transfer switches. In one

- embodiment of the apparatus, there is provided a relay which is operative in response to the removal of the substation receiver from its supporting hook or cradle to connect the handset receiver to be used in lieu of the auxiliary receiving means communicating over a connection of the second type, namely, a direct line connection. While perfectly satisfactory in operation, the arrangement is such that control of the last-mentioned switching relay is achieved only through modification of the subset to include an extra set of hook switch springs, thus rendering a standard substation instrument unsuitable for use.
- 15 It is an object of the present invention to provide in a system of the character described above an improved and exceedingly simple substation circuit arrangement wherein either of two sets of transmitting and receiving apparatus, one set 20 of which comprises a standard subset, may selectively be connected to an established communication connection involving the substation.
- It is a further object of the invention to provide in a system of the character described an improved substation circuit arrangement wherein either of two sets of transmitting and receiving apparatus one set of which comprises a standard 25 telephone subset, may selectively be connected to either of two established connections extending 30 to the substation.
- It is another object of the invention to provide in a system of the character described, wherein two communication channels may simultaneously be established between the executive substation and two different lines of the system, an improved arrangement whereby the channel which is not in use may effectively be short-circuited, thereby to prevent cross talk between the two channels.
- 40 It is a further object of the invention to provide an improved arrangement controllable from the executive substation for marking the line over which incoming calls to the executive substation are routed as busy in the numerical switches having access to this line without busy- 45 ing any of the equipment in the exchange.
- The invention is illustrated as being incorporated in an automatic telephone system of the general arrangement outlined above. In accordance with one feature of the present invention, the arrangement provided at the executive substation for selectively connecting the regular substation subset and the auxiliary transmitting and receiving means to an established connection involving the executive substation comprises a first relay having a winding serially included in the regular substation line over which incoming calls are routed to the substation, and a second relay which functions to switch the connection from one set of transmitting and receiving apparatus to the other. The first relay is arranged to be energized when a loop circuit is established by way of the above-mentioned line, which occurs when the receiver of the subset is removed from its supporting element. The operating circuit for the second relay is jointly controlled by the first relay, the special automatic switching equipment and the transfer switching apparatus, mentioned above. More particularly, with either the special switching equipment or the transfer switching apparatus operated, the operating circuit for the second relay is completed in response to operation of the first relay. This second relay not only functions 75 to perform the line switching operations noted,

but, in addition, functions to complete a holding circuit serially including its own winding and the winding of the first relay, and renders the auxiliary receiving means inoperative by short-circuiting the input channel thereto. The indicated holding circuit is interrupted to release the two relays and restore the normal circuit arrangement when the receiver of the subset is replaced upon its supporting element.

In accordance with another feature of the invention, the above-mentioned arrangement for rendering inactive the one of the two established communication channels extending to the executive substation which is not in use, comprises apparatus controllable by the transfer means for short-circuiting the inactive channel. More particularly, the transfer relay, which responds to operation of the transfer switch to select the desired channel is provided with contacts for effectively short-circuiting each of the two channels when not in use.

In accordance with a further feature of the invention, the apparatus for guarding the executive substation against incoming calls routed over the regular substation line comprises apparatus controllable from the substation for busying the line to the automatic switching equipment having access thereto. More particularly, a path, jointly controlled by the transfer and answer switches, is provided for impressing a line busying potential upon the private conductor of the line, thereby to prevent seizure of the line by the automatic switches. By virtue of this arrangement none of the automatic switching equipment is tied up or held out of service as a result of busying of the line.

Further features of the invention pertain to the particular arrangement of the apparatus whereby the above and additional operating features are attained.

The novel features believed to be characteristic of the invention are set forth with particularity in the appended claims. The invention, both as to its organization and method of operation, together with further objects and advantages thereof, will best be understood by reference to the specification, taken in connection with the accompanying drawings, in which Figures 1 to 6, inclusive, taken together, illustrate a telephone system having incorporated therein the above-outlined features of the present invention, and Fig. 7 is a diagram illustrating the manner of assembling the other figures of the drawings to form a unified system.

Referring now more particularly to Figs. 1 to 6 of the drawings, the equipment there illustrated is, with the exception of the substation apparatus shown in Fig. 1 and the substation apparatus 600 shown in Fig. 6, included in an automatic exchange of the type frequently used to provide telephone facilities between the offices of a large manufacturing organization. This type of exchange is commonly known as a private automatic exchange. Extending to the exchange and terminating in automatic switching equipment diagrammatically illustrated at 320 are a plurality of substation lines, three of which are indicated at 321, 322 and 323. The ends of the lines remote from the exchange terminate in substations of the automatic type, that associated with the line 321 being diagrammatically illustrated at B and that associated with the line 322 being indicated A. The line 323 extends to a special or executive substation of the character mentioned above and includes two line

conductors C327 and C328 and a private or control conductor C329. The automatic equipment 320 comprises the usual subscriber-controlled automatic switches for setting up connections between the telephone lines of the system. More particularly, these switches are, in accordance with conventional practice, divided into two classes, namely, non-numerical switches, such, for example, as line finder or line switches, and 10 numerical switches, such, for example, as selector and connector switches, which latter switches are responsive to impulses transmitted thereto over calling ones of the telephone lines and function to perform the usual line group, subgroup 15 and unit selecting operations. The connector switches at which the lines terminate are, in accordance with conventional practice, equipped to perform the usual auxiliary functions of: testing a selected called line to determine the idle 20 or busy condition thereof, returning busy tone over the calling line in the event a selected called line is found busy, and projecting ringing current over a selected called line to actuate the signal device at the substation in the event the 25 called line is idle at the time it is tested. Further in accordance with conventional practice, the lines extending to the automatic switching equipment 320 are, when busy, guarded against seizure by the connector switches having access 30 thereto through the application of ground or line busying potential to the control conductors thereof. For example, when the line 323 is busy, ground potential is impressed upon the control conductor C329 so that none of the connector 35 switches having access to this line may seize the line.

The substation apparatus 600 and the apparatus provided at each of the substations A, B, etc., may be of any desired commercial construction 40 and arrangement. In brief, this apparatus may comprise the usual handset type of transmitter and receiver, a cradle or hook comprising supporting means for the receiver, a cradle or hook switch, a ringer, and an impulsing device for 45 transmitting switch control impulses by way of the associated lines to the automatic switching equipment 320 located in the line terminating exchange. Preferably, the elements of each substation circuit are connected and arranged to 50 form the well-known anti-side-tone circuit, whereby operation of the substation transmitter does not cause operation of the substation receiver.

As pointed out above, the present invention 55 relates to the provision of improved apparatus for increasing the utility of the available telephone facilities at the executive substation where the substation apparatus 600 is located. With the apparatus thus far described, communication 60 connections may be established between the executive substation and any of the other substations associated with lines terminating at the automatic switching equipment 320 in the usual manner. More particularly, on regular calls 65 initiated at the executive substation, the calling device or dial operated impulsing device included in the apparatus 600 is actuated in the usual manner causing impulse trains to be transmitted to the automatic switching equipment 70 320. An auxiliary dial operated calling device 350 may also be provided if desired, this device being required for initiating calls under certain conditions of operation described in detail hereinafter. The automatic switching equipment 75 responds to impulse trains transmitted thereto by

routing the connection to the desired called line. All calls incoming to the executive substation are routed by way of the regular automatic switching equipment 320 provided in the exchange and the line 323 to the substation apparatus 600, the signal device or ringer 641 embodied in this apparatus being energized in response to ringing current projected over the line 323 following seizure of the line by one of the connector switches included in the automatic 10 switching equipment 320.

For the purpose of routing calls from the executive substation directly to certain of the frequently called subordinate lines terminating at the automatic switching equipment 320 without operating a calling device of the type conventionally used in automatic systems and without the delay incident to the operations required to set up a connection in a manual system, there is provided automatic switching means comprising a rotary switch 310 having bank contacts at which the group of subordinate lines terminate. This switch is a standard twenty-five point rotary switch and comprises four sets of bank contacts 311 to 314, inclusive, wipers 315 to 318, inclusive, respectively associated with the enumerated contact sets, and means comprising a motor magnet 319 for driving the enumerated wipers over the contacts of their respective associated sets. As indicated, the contacts in the two sets 313 and 314 terminate the line conductors of the respective subordinate lines which are directly accessible to the executive substation, and the contacts in the set 312 terminate the private or control conductors of the subordinate lines. The contacts of the fourth contact set 311 terminate conductors extending by way of the cable 295 to the contact springs of a group of coding relays shown in Fig. 2. These conductors individually correspond to the subordinate lines and are included in marking circuits by means of which operation of the switch 310 is controlled. Since the control apparatus described hereinafter is only arranged to provide direct calling facilities to twenty subordinate lines only twenty of the contacts of each contact set embodied in the switch 310 are used, the remaining contacts being left blank. The switch 310 is arranged to be controlled by the group of coding relays shown in Fig. 2 and by the control apparatus 415 illustrated in Figs. 4 and 5. More particularly, the coding relays shown in Fig. 2 and indicated at R200, R210, R220, R230, R240, R250 and R260, respectively, are arranged to be energized in combinations of three in response to the selective operation of any one of the plurality of calling switches illustrated in Fig. 1. These switches, which are indicated at 100 to 109, respectively, individually correspond to the lines forming the group of subordinate lines directly accessible to the executive substation. Each of the enumerated calling switches is of the key operated type and is operable from a normal position to either of two off-normal positions individually corresponding to two subordinate lines. Each of the switches is of the well-known locking type, such that, when once operated to an off-normal position, it remains in its operated position until manually restored to normal. The contact springs of the calling switches are wired in the manner illustrated so that, when any one thereof is operated to one of its two off-normal positions, three of the coding relays shown in Fig. 2 are caused to operate in the manner described in detail hereinafter to complete one of

the above-mentioned marking paths extending to one of the contacts in the set 311 of the rotary switch 310, thereby to identify the called line desired by the calling party.

- 5 The line wipers 317 and 318 of the rotary switch 310 are arranged to be connected by way of a link line comprising the conductors C335 and C339 to a repeating transformer 500 through operation of the control apparatus indicated generally 10 at 415. This apparatus comprises a start relay R450 which is arranged to be energized in response to any one of the calling switches shown in Fig. 1 and functions to initiate the operation of the rotary switch 310 to select a desired called line. Operation of the rotary switch is controlled 15 by the three relays R420, R430 and R440, of which the relays R430 and R440 directly control the stepping operation of the switch 310 and the relay R420 is a test relay for arresting the operation of 20 the rotary switch when its wipers are operated to a position corresponding to a desired called line. The relay equipment also includes a pair of relays R400 and R410 which function to test the condition of a selected called line to determine whether 25 it is idle or busy. More particularly, the slow-to-release relay R410 is a busy relay which is operative to return busy tone to the executive substation in the event a selected called line is found busy, and the slow-to-operate relay R400 is operative 30 in the event a selected called line is found idle and is arranged to control the ringing relay R560, shown in Fig. 5. The busy relay R410 also functions as a device for impressing a background signal on an established connection involving a 35 busy subordinate line called from the executive substation. The apparatus 415 also includes a ring cutoff relay R550 and a back bridge or called party answer relay R510, which relays are arranged to perform the functions conventionally 40 required of relays of this character.

As indicated above, auxiliary transmitting and receiving means are provided at the executive substation for use in communicating over connections established through operation of the auxiliary or special switching means just described. The auxiliary transmitting means comprises a microphone 135, and the auxiliary receiving means comprises a sound reproducing device in the form of a loud speaker, diagrammatically 45 illustrated at 136, connected in tandem with a signal amplifier including the vacuum tube 620. The auxiliary transmitting and receiving means are interconnected with an anti-side-tone impedance network indicated generally at 630 to 50 form a substation circuit of the well-known anti-side-tone type having line terminals 643 and 644 arranged to be connected by way of a link line including the conductors C575 and C576 to one winding of the repeating transformer 500 or by 55 way of a second link line comprising the conductors C296 and C297 to one winding of a second repeating transformer 300, shown in Fig. 3. More particularly, the anti-side-tone impedance network 630 comprises an induction coil or transformer 610 including five windings 611 to 615, inclusive, the last-mentioned of which is coupled to the primary winding 616 of an input transformer 618 having its secondary winding 617 connected 60 across the non-adjustable terminals of a voltage 65 divider resistor 619. The adjustable terminals of the resistor 619 are coupled to the control grid 621 and the cathode 622 of the tube 620. The tube 620, which is of the well-known pentode type and includes a directly heated cathode, is provided 70 with an output circuit comprising the pri- 75

mary winding 628 of an output transformer 627 connected in series with a source of anode potential between the anode 623 and the cathode 622. For the purpose of biasing the control grid 621 negatively with respect to the cathode 622, there is provided a resistor 625 which is commonly included in the output circuit of the tube and the energizing circuit for the cathode 622. The anode current source is by-passed for signal frequency currents by a condenser 626. The secondary winding 629 of the transformer 627 is connected to impress the signal voltage developed thereacross upon the input terminals of the loud speaker 136 through a volume control potentiometer 141. This potentiometer includes an 15 adjustable contact carrying arm 145 so arranged that adjustment of the arm varies the magnitude of the signal voltage impressed upon the input terminals of the loud speaker 136 without substantially changing the value of the resistance 20 connected in shunt with the transformer secondary winding 629. By this arrangement, adjustment of the signal input level to the loud speaker 136 may be achieved, in a well-known manner, without changing the output impedance into 25 which the tube 620 operates and, hence, without introducing distortion into the reproduced output of the loud speaker 136.

The anti-side-tone impedance network 630 includes, in addition to the transformer 610, a 30 pair of line balancing circuits which are arranged selectively to be included in the network and are individually effective, under different operating conditions, to balance the circuit so that, during operation of the microphone 135, no substantial portion of the developed signal voltage is impressed on the input circuit of the amplifier tube 620. The first of the two balancing networks comprises an adjustable inductance element 631 connected in series with an adjustable resistor 40 632, and the second network similarly comprises an adjustable inductance element 631' connected in series with an adjustable resistor 632'. As shown, the transmitter microphone 135 is included in a substantially closed transmission circuit comprising this microphone, a low impedance condenser 139, and the primary winding 138 of a coupling transformer 137. This transformer is provided with a secondary winding 140, one terminal of which is connected by way of the conductor C146 to the junction point between the two transformer windings 611 and 612 and the other terminal of which is connected by way of the conductor C147 to the junction point between the two transformer windings 613 and 614. The two junction points noted form the conjugate terminals of the anti-side-tone bridge circuit, which is effectively formed when the auxiliary substation equipment is connected for use in communicating over an established connection. More particularly, signal currents traversing the secondary winding 140 of the transformer 137 during operation of the microphone 135 divide at the two junction points noted, portions of the currents traversing a path comprising the two windings 611 and 613 and one of the two balancing circuits, described above, and other portions of the currents traversing the two windings 612 and 614 and the established loop circuit extending to the repeating transformer 500 or the repeating transformer 300. By suitably proportioning the impedance values of the elements respectively included in the two balancing circuits, the currents traversing the windings 613 and 614 are rendered substantially equal in magnitude and 75

opposite in phase at all frequencies within the audio range irrespective of which of the two repeating transformers 300 and 500 is included in the established connection. Similarly, when the impedance values of the elements included in the balancing circuits are proportioned in the manner indicated, the signal currents respectively traversing the two windings 611 and 612 are rendered substantially equal in magnitude and 10 opposite in phase at all frequencies within the audio range. Thus, during operation of the transmitter microphone 135, the currents traversing the windings 611, 612, 613 and 614 cause substantially equal and opposite signal voltages 15 to be induced in the secondary winding 615, so that substantially no signal energy is delivered to the input circuit of the vacuum tube 620. By virtue of this arrangement, suppression of the side tone is achieved.

20 For the purpose of utilizing the auxiliary transmitting and receiving means to answer calls incoming to the executive substation and routed by way of the substation line 323, and for the further purpose of permitting the auxiliary transmitting and receiving means selectively to be connected for use in communicating over either of two simultaneously established connections, each extending to the executive substation, there are provided an answer switch 111, a transfer switch 25 110, the repeating transformer 300, the link line comprising the two conductors C296 and C297, and two control relays R270 and R520. The key operated switches 110 and 111 are of the well-known locking type. The transfer switch 110 in 30 combination with the start relay R450 also forms a part of apparatus, controllable from the executive substation for marking the line 323 as busy in the bank contacts of the connector switches having access thereto. Both of the two relays 40 R270 and R520 are arranged to be energized in response to the operation of the answer switch 111, the first thereof being operative to condition the signal amplifier comprising the tube 620 for operation, and also to complete an auxiliary 45 loop circuit extending to a distant subordinate substation and terminated at the windings 303 and 304 of the repeating transformer 300. Arranged to be serially included in an established auxiliary loop circuit is an adjustable resistor 306 50 for conducting direct current and by-passed for signal frequency currents by a condenser 305. The relay R270 conditions the signal amplifier for operation by supplying anode and cathode energizing voltages to the tube 620 over circuits 55 traced hereinafter. In this regard, it is pointed out that the tube 620 is of the well-known C-33 type, which type of tube requires only a low anode voltage to provide reasonably good amplification. Hence, the exchange battery is used to supply 60 anode and screen voltages to this tube. The exchange battery also supplies energizing current to the cathode 622 of the tube, a voltage dropping resistor 624 being serially included in the cathode energizing circuit for the purpose of fixing the 65 resistance of the circuit so that the rated current of the cathode heater traverses the circuit.

The relay R520, which is energized in response to operation of the answer switch 111 and de-energized in response to the subsequent operation 70 of the transfer switch 110, is arranged to transfer the link line C515, C516, leading to the input terminals 643 and 644, from a connection with the winding 501 of the repeating transformer 500 to a connection with the winding 301 of the repeating transformer 300. This relay also func-

tions selectively to include the two balancing circuits, described previously, in the anti-side-tone impedance network 630 and to short-circuit the communication channel not in use, all in the manner pointed out more in detail hereinafter. In order to remind a user of the executive substation equipment that the answer switch 111 is in its operated or off-normal position, there is provided a signal lamp 126 which is arranged to be energized in response to the operation of the switch 111 to its off-normal position.

For the purpose of preventing an established connection extending to one of the subordinate substations from being reestablished after the usual release operation is performed at the subordinate substation and before the connection is released at the executive substation, there are included in the control apparatus 415 two relays R530 and R540, the first of which is of the slow-to-operate type, and the last-mentioned of which 20 is of the slow-to-release type. More particularly, current for energizing the transmitter microphone 135 is normally supplied to this microphone over a circuit including the winding of R540. When, however, a release operation is performed at a 25 subordinate substation involved in an established connection extending to the executive substation, the relay R540 cooperates with the back bridge relay R510 to cause the operation of the relay R530, and the last-mentioned relay functions to 30 open the circuit for supplying energizing current to the transmitter microphone 135 and to maintain this circuit open so long as the connection is not released at the executive substation.

For the purpose of rendering the inclusion of 35 the regular substation transmitter and receiver in an established direct call connection under the control of the hook or cradle switch conventionally included in the regular substation apparatus 600, the three relays R670, R680 and R690 40 are provided. The arrangement is such that, when the transmitter and receiver hand set is being supported upon its hook or cradle, the loud speaker 136 and the microphone 135 are utilized as the transmitting and receiving means, respectively, and, when the substation hand set is removed from its supporting hook or cradle, the transmitter and receiver embodied therein 45 are substituted for the elements 136 and 135 as the receiving and transmitting means to be used. 50

In order to provide secretary calling facilities there is also provided a call buzzer 642 which is arranged to be energized in response to operation of a non-locking call key 142 over a circuit including one conductor C149 of the two leads coupling the loud speaker 136 to the output transformer 627. It will be noted that a circuit including the windings of the loud speaker 136, the conductor C148 and the transformer winding 629 is connected in parallel with the conductor C149 comprising a part of the energizing circuit for the buzzer 642. The impedance of this parallel circuit is, however, so high as compared with the impedance of the conductor C149, that it is traversed only a negligible portion of the current for energizing the buzzer. Hence, operation of the buzzer does not cause any substantial reproduction of the pulsating direct current by the loud speaker.

Although the apparatus shown in detail in Figs. 1 to 6, inclusive, may be arranged in any desired manner, it is contemplated that only the apparatus shown in Fig. 1 and the substation apparatus 600 shall be located in the office of the executive for whose use it is provided. It is 75

further contemplated that the remaining apparatus illustrated in the drawings with the exception of the buzzer 642 shall be conveniently located in the exchange terminating the various lines of the system, a suitable multiconductor cable being provided for interconnecting the circuit elements to provide the circuit arrangement depicted in the drawings and described above.

Referring now more particularly to the operation of the special switching equipment to establish a connection to one of the regular automatic substations and assuming that the substation A is being called, the call is initiated by operating the calling switch 100 to the particular off-normal position corresponding to the called substation. More particularly, if the substation A is being called, the key switch 100 is operated from its normal position to its lower off-normal position to close the springs of the three sets 114, 115 and 116. As indicated above, three of the coding relays illustrated in Fig. 2 respond to the operation of any one of the key switches to an off-normal position to provide a marking path for marking the particular called line in the contact level 311 of the rotary switch 310. In the case under consideration, when the springs 114, 115 and 116 are closed, circuits are completed for energizing the three relays R200, R210 and R220, which circuits commonly include the winding of the start relay R450. The operating circuits for the three relays noted may be considered as a single circuit extending from battery at the lower terminal of the winding of R450 by way of this winding to C293, where it divides, one branch extending by way of the winding of R220, C132 and the springs 114 to the grounded conductor C127; a second branch extending by way of R210, C133 and the springs 116 to the grounded conductor C127; and the third branch extending by way of R200, C134 and the springs 115 to the grounded conductor C127. When energized over the above-traced circuits, the four relays R200, R210, R220 and R450 operate and the first three thereof function to complete a marking path identifying the line 322 as the line being called. This marking path extends from ground at RA201 by way of RA211, RA221 and C277 to the twenty-fifth contact of the contact set 311. Due to the above-described arrangement of the coding relays, none of the other marking paths individually corresponding to the other lines directly accessible to the special equipment are completed.

As a further example of the manner in which the coding relays operate in response to selective operation of the calling switches, it is pointed out that, if the switch 100 is operated to close the contact springs 112, 113 and 117, a series-parallel circuit is completed for energizing the three coding relays R200, R210 and R230, and the start relay R450. In this case, the two relays R200 and R210 are energized over circuits substantially similar to the branch circuits traced above and the relay R230 is energized over a branch circuit extending by way of C293, the winding of R230, C131 and the contact spring 117 to the grounded conductor C127. When the three relays R200, R210 and R230 operate, a marking path is completed for applying ground potential to the twenty-fourth contact of the set 311, this path extending from ground at RA201 by way of RA211, RA231 and C278 to the twenty-fourth contact of the set 311.

Again, if the tenth calling switch 109 is operated to its lower off-normal position, the springs

121, 122 and 123 are closed to complete a series-parallel circuit for energizing the three relays R200, R240 and R260 in series with the relay R450. In this case the relay R200 is energized over a branch circuit extending by way of C134 and the springs 123 to the grounded conductor C127; the relay R240 is energized over a branch circuit extending by way of C130 and the springs 122 to the grounded conductor C127; and the relay R260 is energized over a branch circuit extending by way of C128 and the springs 121 to the grounded conductor C127. Upon operating, the three relays complete a path extending from ground at RA261 and by way of RA246, RA203 and C279 for impressing marking ground on the nineteenth contact of the contact set 311. It will be apparent from the foregoing description that by selectively operating the calling switches, the coding relays may be caused to operate in different combinations of three, thereby selectively to complete the twenty marking paths extending to the respective contacts of the contact set 311.

In any case when three of the coding relays are energized the start relay R450 is also energized and, upon operating, completes, at RA452 and RA453, respectively, paths commonly including the grounded armature RA559 and C470 for applying ground to the tone apparatus and ringing machine start conductors C407 and C408, thereby to initiate the operation of the tone apparatus and the ringing apparatus in the usual manner. At RA454, the relay R450 applies ground to the amplifier start conductor C294, thereby to condition the amplifier comprising the tube 620 for operation. More particularly, operation of the relay R450 results in the connection of the positive terminal of the exchange battery to C294, so that anode potential is impressed through the primary winding 628 of the output transformer 627 on the anode 623 of the vacuum tube 620. Operation of the relay R450 also results in the completion of a circuit for energizing the cathode 622 of the tube 620, this circuit extending from the grounded positive terminal of the exchange battery at RA454 by way of C294, the voltage dropping resistor 624, the cathode 622 and the biasing resistor 625 to the negative terminal of the exchange battery. It will be noted that positive screen potential is applied to the screen electrode of the tube 620 directly from the positive terminal of the exchange battery over the path including the conductor C294. At RA455, the relay R450 prepares a path, traced hereinafter for applying ground potential to the private conductor C329 of the line 323.

At RA451, the relay R450 completes a circuit for energizing the slow-to-operate relay R430, this circuit extending from ground at RA451 by way of RA422, RC423, C336, the armature 319, C337 and the winding of R430 to battery. The relay R430 operates, after an interval, and, at RA431, prepares a circuit, traced hereinafter, for energizing the relay R420 when the wipers of the rotary switch 310 are stepped to the position corresponding to the selected called line 322. At RA432 and RC433, the relay R430 also prepares a test circuit, traced hereinafter, for energizing the busy relay R410 in the event the selected called line is busy at the time the switch 310 is operated to the position corresponding to the called line. At RA435, the relay R430 completes a circuit for energizing the relay R440, this circuit extending from ground at RA451 by 75

way of RA422, RC423, C336, the armature 319', C337, RA435 and the winding of R440 to battery.

When energized over the circuit just traced, 5 the relay R440 operates to complete, at RA441, a circuit for energizing the motor magnet 319 of the switch 310, this circuit extending from ground at the grounded contact RC427 by way of RA426, RA441, C338, and the winding of the 10 magnet 319 to battery. Upon operating, the magnet 319 steps the wipers 314 to 318, inclusive, of the switch 310 one step and interrupts, at its associated armature 319', the above-traced 15 operating circuits for the two relays R430 and R440. The relay R440 immediately restores to interrupt, at RA441, the operating circuit as traced above for the magnet 319, whereupon this magnet restores its associated armature 319' to recomplete the operating circuits for the two relays R430 and R440, respectively. When the operating circuit for R440 is again completed, this 20 relay operates to recomplete the above-traced circuit for energizing the magnet 319, causing this magnet to again step the enumerated wipers of the switch 310 a second step and to again 25 interrupt the operating circuits for the two relays R430 and R440. The above-described interaction between the relay R440 and the magnet 319 continues until such time as the wipers of the switch 310 are stepped to the position corresponding to the called line 322, or until the wiper 315 is moved into engagement with the contact marked with ground over the above-traced 30 marking path. During the interaction between the relay R440 and the magnet 319, the relay R430, due to its slow-to-release characteristic, stays operated.

When the wiper 315 of the switch 310 is operated into engagement with its associated 40 twenty-fifth contact, the above-mentioned circuit is completed for energizing the relay R420, this circuit extending from the grounded conductor C277 by way of the twenty-fifth contact of the set 311, the wiper 315, C333, RA431 and the lower winding of R420 to battery. When 45 its lower winding is energized over the circuit, just traced, the relay R420 immediately operates to interrupt, at RA426 and RC427, the above-traced circuit for energizing the magnet 319, 50 thereby to arrest the interaction between this magnet and the relay R440 and to prevent further movement of the wipers embodied in the rotary switch 310. At RA425, the relay R420 completes a holding circuit for itself, this holding 55 circuit extending from the grounded conductor C333, by way of RA425 and the upper winding of R420 to battery. At RA422 and RC423, the relay R420 interrupts a point in the circuits over which R430 and R440 are being held energized, causing these two relays to restore. At RA422 and RC424, the relay R420 60 prepares a holding circuit, traced hereinafter, for R560.

At RA421, the relay R420 completes the above- 65 mentioned circuit for testing the called line 322 to determine the idle or busy condition thereof. In this regard and as previously explained, the automatic switching equipment provided in the exchange 320 is conventionally arranged so that, 70 when the line 322 is busy, ground potential is present upon the control conductor C324 thereof, whereas, if the line is idle, battery potential appears on this control conductor. Assuming the selected called line 322 is busy, the busy relay 75 R410 is energized over the above-mentioned test

circuit, which circuit extends by way of the control conductor C324, the twenty-fifth contact of the set 312, the wiper 316, C334, RA421, RA432, RC433 and the winding of R410 to battery. Upon operating, the busy relay R410 interrupts, at 5 RA411, a point in the circuit, traced hereinafter, for energizing the slow-to-operate control relay R400. At RA412, the relay R410 completes a holding circuit for itself, this circuit extending by way of the conductor C334, RA421, RA412 10 and the winding of R410 to battery.

The relay R410, upon operating, functions to complete a circuit for impressing busy tone voltage on the input circuit of the signal amplifier comprising the vacuum tube 620. Specifically, 15 the path of the busy tone current extends from the ungrounded terminal of the busy tone source, not shown, by way of the busy tone conductor C406, the condenser 404, RA413, C465, RC529', RA528, C576, RA676, the transformer windings 20 612 and 611, the inductance element 631, the resistor 632, C572, RC522, RA521, C574, the transformer windings 613 and 614, RA671, C575, RA524, RC525 and the upper half of the winding 501 to the grounded terminal of the busy 25 tone source at the grounded center tap 502 of the winding 501. This current causes an induced voltage to be developed in the transformer winding 615 which is impressed through the coupling transformer 618 between the input electrodes of the tube 620, and the amplified output energy is delivered through the transformer 627 and the volume control potentiometer 141 to the 30 loud speaker 136 for reproduction. The reproduced busy tone signal indicates to the calling 35 party that the desired connection cannot immediately be established.

Presumably, the substation at which the illustrated special equipment is located is that of an important official or executive, such that calls 40 originating at this substation and intended for the various subordinate lines are of sufficient importance to warrant direct attention on the part of the called parties. For this reason, the busy relay R410 is so arranged that it functions to 45 impress a background signal on a selected subordinate line which is tested and found busy. More particularly, when the relay R410 operates, it completes a path for impressing the voltage of the ringing current source upon the previously 50 established loop circuit of which the called line forms a part. In the case under consideration, the path of the ringing current extends from the ungrounded terminal of the ringing current source, not shown, by way of the ringing current 55 conductor C405, the condenser 402, RA414, C339, the wiper 318, the twenty-fifth contact of the set 314, the line conductor C326, the receiver at the called substation A, the line conductor C325, and through one winding of the back bridge relay 60 conventionally provided in the operated connector switch of the switch train leading to the line 322, to the grounded terminal of the ringing current source. The condenser 402 included in this path is selected of a value such that the 65 current traversing the above-traced path is insufficient to produce a signal which will interfere with the ensuing conversation over the established connection including the line 322, but is of sufficient strength to indicate that the substation A is being called from the executive substation.

Following the operation of the busy relay R410, no further operation of the apparatus occurs until the partially established connection is re- 75

leased. To release the connection it is only necessary to restore the operated key switch 100 to its normal position, thereby to interrupt the above-traced operating circuits for the four relays R200, R210, R220 and R450, causing all of these relays to restore. When the first three of the enumerated four relays restore, the above-traced marking path extending to the twenty-fifth contact of the contact set 311 in the switch 10 310 is interrupted. When this path is interrupted, the holding circuit for R420 is broken, causing this relay to restore to interrupt, at RA421, a point in the above-traced holding circuit for the busy relay R410. Thus, the three 15 operated relays R410, R420 and R450 are caused to restore and the common apparatus 415 is conditioned for further use. In this regard, it will be noted that when the relay R450 restores, it 20 interrupts, at RA454, the path for applying ground to the amplifier start conductor C294, whereby the signal amplifier including the tube 620 is rendered inactive. Upon restoring, the relay R450 also interrupts, at RA451, a point in the operating circuits for R430 and R440 and, 25 at RA452 and RA453, the two paths described above for applying ground to the tone apparatus start conductor C407 and the ringing apparatus start conductor C408.

If the calling party desires he may disregard 30 the busy signal and wait until the established connection is cleared out, in which case the apparatus 415 operates to extend the connection to the called line 322 immediately the called line becomes idle. In this regard it is pointed out 35 that the above-traced holding circuit for the busy relay R410 extends to ground as applied to the control conductor C324. Hence, when the line 322 becomes idle and ground is removed from C324, the holding circuit for R410 is interrupted causing this relay to restore. Upon 40 restoring, the busy relay R410 permits ringing current to be projected over the called line in the manner described immediately hereinafter.

In the event the called line 322 is idle at the 45 time it is selected by the switch 310, battery potential is present on the control conductor C324 thereof and, hence, the busy relay R410 is not energized. A short time interval after the switch 310 is operated to the position corresponding to the line 322 or, more particularly, a short time 50 interval after the relay R420 operates, the slow-to-release relay R430 restores to interrupt, at RA432 and RC433, a point in the previously traced testing circuit by way of which the busy 55 relay R410 is energized. At RA432 and RC434, the relay R430, upon restoring, completes a circuit for energizing the control relay R400, this circuit extending from ground at RA451 by way of RA411, the winding of R400, RC434, RA432, 60 RA421, C334, the wiper 336 and its associated twenty-fifth contact to battery as impressed upon the control conductor C324 of the idle line 322. Shortly following its energization over the circuit just traced, the slow-to-operate relay R400 65 operates to complete, at RA401, a circuit for energizing the ringing relay R560, this circuit extending from ground at RA451 by way of RA422, RC424, RA401, C463 and the winding of R560 to battery. Upon operating, the relay 70 R560 completes, at RA561, a holding circuit for itself, which circuit extends from ground at RA451 by way of RA422, RC424, C462, RA567 and the winding of R560 to battery. At RA568, the relay R560, upon operating, applies ground 75 to the control conductor C324 of the called line

322, thereby to mark this line as busy in the bank contacts of the connector switches to which it extends. Specifically, the above-mentioned marking path extends from ground at RA568 by way of C464, RA421, C334, the wiper 316 and its associated twenty-fifth contact to the control conductor C324. At RA565 and its associated grounded contact RC566, the relay R560 prepares a locking circuit, traced hereinafter, for the slow-acting ring cut-off relay R550. At 10 RA561 and RA562, the relay R560 completes a path for projecting ringing current over the called line 322, thereby to energize the signal device at this substation. Specifically, the path traversed by the ringing current extends from 15 one terminal of the ringing current source, not shown, by way of C405, C467, RA557, RA561, C339, the wiper 318 and its associated twenty-fifth contact, the line conductor C326, the signal device at the called substation, the line conductor C325, the wiper 317, C335, RA563, RA562, RA552, RC553 and the upper winding of R550 to the other terminal of the ringing current source. The resulting operation of the signal device provided at the called substation indicates that this substation is being called. The relay R560 also completes a path for transmitting ring-back-tone energy to the input circuit of the signal amplifier tube 620, this path being substantially the same as that traced previously for the busy-tone current, but extending from the ringing current source by way of C405, 20 the condenser 403, C468, RA569, RA558 and RA542, rather than by way of C406, the condenser 404, RA413 and C465. The ring-back- 25 tone energy delivered to the input circuit of the amplifier tube 620 is amplified by this tube and delivered to the loud speaker 136 for reproduction, thereby to indicate to the calling party that the desired called substation is being rung. 30 35

The desired conversational connection is completed when the call is answered at the called substation A. More particularly, when the receiver at the substation A is removed from its hook, a direct current bridge is placed across 45 the line conductors C325 and C326 of the line 322 to complete a direct current circuit substantially similar to that, traced previously and traversed by the alternating ringing current, for energizing the upper winding of the ring cutoff 50 relay R550. When its upper winding is energized the relay R550 first closes the "X" contacts associated with RA556, thereby to complete the above-mentioned holding circuit for itself, this circuit extending from ground at RC566 by way 55 of RA565 and the two windings of R550 in series to battery. At RA552 and RA557 and their respective associated resting contacts, the relay R550 opens two points in the above-traced path for projecting ringing current over the selected 60 called line 322 and, in so doing, opens two points in its own operating circuit. At these same armatures and their respective associated working contacts, the relay R550 extends the called substation loop circuit to the repeating transformer 65 500, thereby to complete a circuit including this loop circuit for energizing the back bridge or called party answer relay R510.

When the relay R510 operates, it completes, at RA511 and RC513, a circuit for energizing the 70 slow-to-release relay R540, this circuit extending by way of RA532, C571, C150, the transmitter microphone 135, the winding 138, C151, C570 and through the winding of R540 to battery. Current for energizing the transmitter micro- 75

phone 135 is conducted to the microphone over the circuit just traced. Upon operating, the relay R540 prepares, at RA541, a circuit, traced hereinafter, for energizing the relay R530. At 5 RA542, the relay R540 opens a further point in a path for conducting ring-back-tone current by way of the anti-side-tone impedance network 630 to the input circuit of the amplifier tube 620.

Following the operation of R540, the desired 10 conversational circuit is completely established, talking battery being supplied to the loop extending to the called substation A through the windings of the back bridge relay R510, and talking battery being supplied to the transmitter microphone 135 over the circuit, traced above, for energizing the relay R540. Signal currents incoming to the special substation and traversing the windings 503 and 504 of the repeating transformer 500 cause induced voltages to be 20 developed in the winding 501 coupled to the two windings 503 and 506, whereby signal currents corresponding to the incoming signal currents are caused to flow through the anti-side-tone impedance network 630. More particularly, the 25 path followed by currents traversing the winding 501 may be traced as extending from the lower terminal of this winding by way of RC529, RA528, C576, RA676, the two windings 612 and 611, the inductance element 631, the resistor 30 632, C512, RC522, RA521, C574, the two windings 613 and 614, RA671, C575, RA524, RC525, back to the upper terminal of the winding 501. The resulting induced voltages developed in the winding 615 are impressed through the coupling 35 transformer 618 and the voltage dividing resistor 619 between the input electrodes of the amplifier tube 620, thereby to cause corresponding amplified currents to flow in the output circuits of this tube. Such currents cause induced voltages to 40 be produced in the winding 629 of the output coupling transformer 627, which voltages are impressed through the potentiometer 141 on the input terminals of the loud speaker 136 for re-production.

45 Audio frequency currents developed by operation of the microphone 135 are caused to circulate in the closed low impedance transmission circuit comprising the primary winding 138 of the transformer 137 and the condenser 139. Such 50 currents cause corresponding induced voltages to be developed in the secondary winding 140 of the transformer 137 which are impressed by means of the two conductors C146 and C147 between 55 opposite terminals of the anti-side-tone impedance network 630. More particularly, signal currents traversing the winding 140 divide at the terminals of the anti-side-tone impedance network and follow the two paths traced previously, whereby the well-known anti-side-tone effect is 60 realized.

The release of the established communication connection is primarily under the control of the calling party. If the called party at the substation A restores his receiver to its hook before the 65 calling key switch 100 is returned to normal, the established called partly loop circuit extending to the repeating transformer 500 is interrupted, causing the back bridge relay R510 to restore in the usual manner. Upon restoring, the relay R150 interrupts, at RA511 and RC513, the above-traced circuit for energizing R540 and, at 70 RA511 and RC512, it completes a circuit for energizing R530, the latter circuit extending by way of RA527, RA541 and the winding of R530 75 to battery. Upon operating, the relay R530 com-

pletes, at RA531, a holding circuit for itself, this circuit extending from ground at RA555 by way of RA531 and the winding of R530 to battery. It is noted that the relay R530, although of the slow-to-operate type, operates to complete its holding 5 circuit before the slow-to-release relay R540 restores to open the operating circuit for R530. At RA532, the relay R530, upon operating, opens a further point in the above-traced operating circuit for R540 and, in so doing, opens a further point in the circuit by way of which energizing current is delivered to the microphone 135. At RA534, the relay R530 applies ground by way of C470 to the two start conductors C407 and C408, thereby to reinitiate the operation of the 15 tone apparatus and the ringing apparatus providing this apparatus is not already in operation. At RA542, the relay R540, upon restoring, completes an alternative path including C469 for impressing busy-tone voltage upon the input 20 circuit of the signal amplifier tube 620, thereby to cause a busy-tone signal to be reproduced by the loud speaker 136. The busy-tone signal produced by operation of the loud speaker 136 indicates to the calling party that the key switch 25 100 has not been restored to normal.

The purpose of providing the relay R530, which 30 operates in response to the release operation performed at the called substation, is that of positively preventing eavesdropping on the part of a subordinate, following the termination of a conversation between the subordinate and the calling executive. Thus, in the absence of this relay and its associated circuits, the called party at the substation A could, after hanging up, again 35 remove his receiver from its hook to recomplete the talking connection, provided the operated key switch 100 was not restored to normal by the calling party. In this regard, it will be appreciated that the back bridge relay R510 would 40 respond to the recompletion of the loop circuit to again complete the circuit for delivering energizing current to the transmitter 135. Obviously, with this connection reestablished, the subordinate could listen to any conversation being carried on in the office of the executive. With the arrangement illustrated, however, the relay R530, 45 upon operating, is held operated independently of the back bridge relay R510 and, in its operated position, holds interrupted, at RA532, the above-traced path by way of which energizing current is delivered to the transmitter microphone 135. Thus, the channel for transmitting signal currents outgoing from the special substation to the called substation is rendered completely inactive and eavesdropping on the part of a subordinate is positively prevented. 50

As indicated above, the common control apparatus 415 is released in response to the restoration of the operated key switch 100 to its 55 normal position. When this switch is returned to normal the three operated coding relays R200, R210 and R220, and the start relay R450 are all caused to restore in the manner pointed out above. When the three enumerated coding relays restore, the above-traced holding circuit for R420 is interrupted, causing the last-named relay to restore and interrupt, at RA422 and RC424, the circuit over which R560 is being held energized. During the restoration of the relay R560, 60 the contact springs RA563 and RC564 are moved into engagement before the loop circuit extending to the called substation is interrupted, providing the called party has not restored his receiver to its hook. When the enumerated springs 65 70 75

are moved into engagement, the condenser 343 is connected through RA551 between the line conductors C339 and C335. This condenser absorbs the voltage transient which occurs when the 5 talking loop is interrupted at RA561 following the restoration of R560 completely to normal and thus prevents the transient from being reproduced as an objectionable "click" by the receiver at the called substation. When 10 R560 falls back, it interrupts, at RA565 and RC566, a point in the holding circuit for the ring cutoff relay R550, whereby the last-mentioned relay is caused to restore. The relay R550, upon restoring, opens at RA551 a point in the 15 path connecting the condenser 343 between the link line conductors C335 and C339. Upon restoring, the relay R550 opens, at RA555, a point in the holding circuit for R530. If R530 is operated, it restores to remove, at RA534, multiple 20 ground from C470. Following the restoration of R530, the common control apparatus 415 is entirely released.

If the executive desires not to be disturbed by incoming calls routed over the line 323 while the 25 above-described direct line call is in progress, he may preclude such incoming calls by operating the transfer switch 110, thereby to mark the line 323 as busy in the bank contacts of the connector switches having access thereto. More particularly, when the start relay R450 operates it prepares a path for impressing ground potential upon the private or control conductor C329 of the line 323. This path may be completed by operating the transfer switch 110 without operating the 30 answer switch 111 and extends from ground by way of the middle and left springs of the switch 111, the middle and left springs of the switch 110, C152, RA273, C251 and RA455 to the private conductor C329. When this path is completed, 35 the line 323 tests busy to all automatic switches attempting to gain access thereto and thus the executive substation is guarded against incoming calls over this line.

Following the completion of the direct line connection in the manner just described, the substation apparatus 600 may, if desired, be used in lieu of the auxiliary transmitting and receiving apparatus in communicating over the connection. Considering the operation of the relays R670, 45 R680 and R690, when the hand set embodied in the apparatus 600 is resting upon its supporting cradle or hook, the loop circuit extending from the substation apparatus 600 by way of the line 323 to the switching apparatus 320 is open and 50 the relays R670, R680 and R690 are deenergized, whereby the line conductors C575 and C576 are connected by way of the armatures RA671 and RA676 and their respective associated resting contacts through to the line terminals 643 and 644 55 of the network 630. Also, with the hand set resting on its supporting means such that the relay R670 is restored, the two line conductors C327 and C328 of the substation line 323 are connected by way of the armatures RA674 and RA675 and 60 their respective associated resting contacts to the line conductors of the cord extending to the substation apparatus 600. So long as all of the calling switches and the answer key switch 111 occupy their respective normal positions, the 65 amplifier start conductor C294 is disconnected from ground so that the operating circuit, traced hereinafter, for R670 is interrupted independently of the hook or cradle switch provided in the 70 substation apparatus 600. Hence, when no direct 75 call connection is established, the substation

apparatus 600 may be utilized in the usual manner in the initiation and answering of calls outgoing from and incoming to the executive substation.

If, after the above-described direct call connection is established, it is desired to use the hand set embodied in the apparatus 600 as the transmitting and receiving means in communicating over the direct call connection, the hand set is removed from its supporting hook or cradle, 10 thereby to connect a direct current bridge between the line conductors of the cord extending to the apparatus 600. As a result, a loop circuit is completed over which the relay R680 is energized, this circuit extending from one side of the 15 exchange battery through one winding of the line relay associated with the line 323 and by way of C327, RA674, the winding of R680, the bridge across the line conductors of the cord extending to the apparatus 600, RA675, C328, and through 20 the other winding of the line relay associated with the line 323 to the other terminal of the exchange battery. When energized over this circuit, the relay R680 operates to complete, at RA681, an obvious circuit for energizing the relay 25 R690. The slow-to-operate relay R690 now partially operates to close the "X" contacts associated with RA693, thereby to complete a circuit for energizing the relay R670, this circuit extending by way of the grounded start conductor C294, 30 RA693, RA692, RA673, and the lower winding of R670 to battery. Shortly thereafter, the relay R690 completes its operation to open, at RA692, a point in the circuit just traced and to prepare, at RA692, an alternative circuit, traced hereinafter, 35 for energizing the lower winding of R670. At RA691, the relay R690 interrupts the path normally short-circuiting its upper winding, thereby to render itself fast to release. The armature springs of the relay R670 are so adjusted that the 40 two armatures RA674 and RA675 are moved from engagement with their respective associated resting contacts and into engagement with their respective associated working contacts before the armature RA692 of the relay R690 is moved out 45 of engagement with its associated resting contact. Thus, upon the initial energization of the lower winding of R670, a holding circuit is completed for this relay and the relay R680 before the operating circuit, just traced, is interrupted. This 50 holding circuit extends from the grounded conductor C294 by way of the upper winding of R670, RA675 and its associated working contact, the closed bridge between the line conductors of the cord extending to the apparatus 600, the winding 55 of R680, RA674 and its associated working contact, and the lower winding of R670 to battery. Energizing current is delivered to the transmitter embodied in the hand set of the apparatus 600 over this holding circuit. Immediately after the 60 completion of the above-traced holding circuit, the armature RA692 of the relay R690 is moved from engagement with its associated resting contact to interrupt the operating circuit for R670.

At RA671 and RA676 and their respective associated resting contacts, the relay R670, upon fully operating, disconnects the line conductors C575 and C576 from the line terminals 643 and 644, respectively, of the anti-side-tone impedance network 630 and connects these line conductors by 70 way of the condensers 678, 679 and 682 to the line conductors of the cord extending to the substation apparatus 600. Thus, the transmitter and receiver incorporated in the substation apparatus 600 are substituted for the auxiliary trans- 75

mitting and receiving means in the established connection.

When the operating circuit for R670 is completed, a relatively heavy current flows through the upper winding of the relay, which current is materially reduced when the operating circuit is broken and the holding circuit for R670 is completed. Due to the collapse of the magnetic field occasioned by interruption of the operating circuit, a relatively large transient voltage tends to be developed across the windings of R670, which, if not absorbed, would be impressed through the condensers 678 and 679 across the repeating transformer winding 501 or the winding 301, depending upon the position of the relay R520. If allowed to assume its full value, such a transient would cause an objectionable click in the receiver being used at the distant end of the connection. To obviate this difficulty, the relay R670 is provided with a set of armature springs associated with RA671 which are included in an obvious path for short-circuiting the signal channel comprising the two line conductors C575 and C576 during the initial operation of R670. The springs of this set are so arranged that they are not moved to the open-circuit position to interrupt the short-circuiting path noted until after the transient is substantially damped out. By this arrangement the transient voltage is not impressed on the signal channel of which the line conductors C575 and C576 form a part, but is dissipated in a closed circuit comprising the condensers 678 and 679, the two windings of R670, the winding of R680 as shunted by the by-pass condenser 682, the exchange battery and RA671.

It will be noted that, when the relay R670 operates to connect the substation apparatus 600 to be used in communicating over the established direct line connection, the line terminals 643 and 40 644 of the anti-side-tone impedance network 630 are open-circuited and, thus, this network is unbalanced so that electrical coupling is incidentally provided between the signal current receiving and signal current transmission paths extending 45 to the loud speaker 136 and from the microphone 135, respectively. Also, acoustical coupling exists between the microphone 135 and the loud speaker 136, and the signal amplifier comprising the vacuum tube 620 is still energized and in condition for operation. Due to the two couplings noted, a local oscillatory condition tends to be set up in the network comprising the signal amplifier, the transmitter 135, the loud speaker 136, and the anti-side-tone impedance network. 50 If this oscillatory condition is allowed to persist, howling or singing results. To obviate this difficulty, the relay R670 is provided with a pair of armature springs for short-circuiting the input circuit to the loud speaker 136 when this relay 55 occupies its operated position. More particularly, when the relay R670 operates, it completes, at RA672, an obvious path for short-circuiting the winding 629 of the transformer 627, thereby effectively to interrupt the local oscillatory circuit, as described above, and to prevent howling during the intervals when the auxiliary transmitting and receiving means are conditioned for operation but are disconnected from an established communication connection.

70 The auxiliary transmitting and receiving means may be substituted for the transmitter and receiver embodied in the substation apparatus 600 by returning the substation hand set to its supporting hook or cradle, thereby to open the 75 direct current bridge across the line conductors

of the cord extending to this apparatus. When this occurs, the above-traced holding circuit for the relays R670 and R680 is interrupted. Thus, the relays R670 and R680 are caused to restore. Upon restoring, the relay R680 opens the operating circuit for R690, causing the last-mentioned relay to restore. The relay R670, upon restoring, disconnects the substation apparatus 600 from the established communication connection; interrupts, at RA672, the short-circuiting path 10 across the winding 629; and reconnects the line conductors C575 and C576 to the line terminals 643 and 644, respectively, of the anti-side-tone impedance network 630.

From the foregoing description, it will be apparent that, when once the relay R670 is operated, it is only deenergized in response to the replacement of the substation hand set upon its supporting hook or cradle. Hence, to release a direct call connection which has been established 15 in the manner previously described and to which the apparatus 600 is operatively connected, it is necessary to restore the operated one of the calling switches of Fig. 1 to normal and to replace the substation hand set upon its supporting hook 20 or cradle. When the operated calling switch is returned to its normal position, the operated relays of Figs. 2, 4 and 5 are caused to restore in the manner described previously, it being noted that, when the start relay R450 falls back, ground 25 potential is removed from the amplifier start conductor C294 to open a point in the operating circuit for the relay R670. When the substation hand set is placed upon its supporting hook or cradle, the operating and holding circuits for 30 the relays R670, R680 and R690 are interrupted in the manner just described.

As indicated above, the substation apparatus 600 is normally connected and arranged to be used in communicating over connections established between the executive substation and one of the other substations on calls incoming to the executive substation. The special substation apparatus illustrated in Figs. 1 to 6, inclusive, is, however, so arranged that the auxiliary transmitting and receiving means comprising the microphone 135 and the loud speaker 136 may, if desired, be used in lieu of the regular substation apparatus 600 to answer incoming calls. For example, if a call is initiated at the substation A 50 and routed by way of the automatic switching equipment 320 and the line 323 to the substation apparatus 600 at a time when the line 323 is idle, ringing current is projected over the line to actuate the signal device 641, thereby to give an 55 audible indication that the executive substation is being called. Obviously, the call may be answered in the usual manner by removing the receiver embodied in the substation apparatus 600 from its associated hook. In this case the 60 resulting sequential operation of the two relays R680 and R690 is without effect since ground potential is not present upon either of the conductors C294 and C694 and, hence, the relay R670 is 65 not energized. Alternatively, the auxiliary transmitting and receiving means comprising the loud speaker 136 and the transmitter microphone 135 may be used. In case the answering party elects to use the last-mentioned means, the answer switch 111 is operated to its off-normal position 70 to close the springs 125 and thereby complete a circuit for energizing the control relay R270. This circuit extends from ground by way of the switch springs 125, the signal lamp 126, C127' and the winding of R270 to battery. Upon oper- 75

- ating, the slow-to-release relay R270 completes a circuit for energizing the relay R520. The last-mentioned circuit extends from ground by way of the springs 125, the springs 124, C152, RA273, and 5 the winding of R520 to battery. When energized over the above-traced circuit, the signal lamp 126 is illuminated to indicate that the answer switch 111 occupies its off-normal position. The relay R270, upon operating, also completes, at RA272, 10 a path for applying ground to the amplifier start conductor C294, whereby the signal amplifier comprising the vacuum tube 620 is conditioned for operation in the manner described previously. At RA272 and RA274, the relay R270 prepares a 15 circuit, traced hereinafter, for energizing the relay R670. At RA271, the relay R270 completes a direct current bridging path between the line conductors C327 and C328 of the called line 323, which path includes the two windings 303 and 20 304 of the repeating transformer 300. More particularly, the bridging path noted extends from the line conductor C327 by way of the winding 304, the resistor 306, C299, RA271, C298 and the winding 303 to the opposite line conductor C328. 25 The operated connector switch by way of which the connection is routed to the line 323 responds to the completion of this path in the usual manner by interrupting the ringing operation.
- As indicated above, the relay R520 is energized 30 in response to the operation of the answer switch 111 to its off-normal position and the resulting operation of the relay R270. When energized, this relay operates to complete, at RA528', the above-traced circuit for energizing R540 and by 35 way of which energizing current is delivered to the transmitter microphone 135. At RA527, the relay R520 opens a point in the above-traced operating circuit for R530, thereby to prevent the last-mentioned relay from operating in response 40 to the operation of R540. At RA523', the relay R520 opens a closed and obvious path normally short-circuiting the winding 301 of the transformer 300. At RA525', the relay R520 completes an obvious path for short-circuiting the winding 45 501 of the transformer 500. The purpose of this channel short-circuiting arrangement is to preclude the possibility of cross talk. To this end, the relay R520 is provided with the two armatures RA523' and RA525', which function to short- 50 circuit the channel not in use in an obvious manner. At RA524 and RA528 and their respective associated resting contacts RC525 and RC529', the relay R520 disconnects the line conductors C575 and C576 from the winding 501 of the repeating coil 500, and, at these same armatures 55 and their respective associated working contacts RC526 and RC529, connects the line conductors C575 and C576 by way of the link line conductors C296 and C297, respectively, to the opposite terminals of the repeating transformer winding 301. Thus, the repeating transformer 300 is incorporated in the newly established talking connection in lieu of the repeating transformer 500, which latter transformer is used on subordinate 60 calls originated at the special substation. Since the impedance characteristics of the loop circuits respectively including the repeating transformers 500 and 300 may be different, it is desirable to provide alternative line balancing circuits ar- 65 ranged alternatively to be included in the anti-side-tone impedance network 630. As described above, with the relay R520 deenergized, the line balancing circuit comprising the inductance element 631 and the resistor 632 is operatively in- 70 cluded in the anti-side-tone impedance network 75

630. When, however, the relay R520 operates, it substitutes the other balancing circuit, namely, that comprising the inductance element 631' and the resistor 632', for the first-mentioned balancing circuit in the anti-side-tone impedance net- 5 work. This is accomplished through the opera- 10 tion of R520 to disconnect, at RA521, the conductor C574, extending to the upper terminal of the winding 613, from the conductor C572 and to connect this conductor to the conductor C573. It will be understood that the line balancing circuit comprising the inductance element 631' and the resistor 632' is adjusted to have a frequency- 15 impedance characteristic substantially matching that of the equivalent impedance of the repeating transformer 300 and the line impedances associated therewith as determined at the line terminals 643 and 644 of the impedance network 630. Similarly, the line balancing circuit comprising the inductance element 631 and the resistor 632 is adjusted to have a frequency-im- 20 pedance characteristic substantially the same as that of the equivalent impedance of the repeating transformer 500 and the line impedances associated therewith as determined at the line terminals 643 and 644 of the network 630.

Following the operation of R520, the desired conversational connection is fully completed. After the connection is completed the answering party may, by removing the telephone receiver 30 or hand set of the substation apparatus 600 from its supporting hook or cradle, release the auxiliary transmitting and receiving means comprising the loud speaker 136 and the transmitter 135 and continue the conversation by using the reg- 35 ular substation transmitter and receiver. When the receiver of the telephone instrument 600 is removed from its supporting element the three relays R670, R680 and R690 respond in the exact manner previously described to disconnect the 40 telephone instrument of the apparatus 600 from the line 323 and to connect this instrument to the link line conductors C575 and C576. It will be noted that with the relays R270, R520 and R670 operated, the substation apparatus 600 is 45 operatively connected to the line 323 over an alternative channel, namely, that including the link line C575, C576, the link line C296, C297, and the transformer 300. With the relays R270 and R520 operated it is obvious that, by restoring and 50 removing the substation hand set from its sup- 55 porting hook, the answering party may substi- 60 tute one set of apparatus for the other as many times as desired during a single conversation. When, however, the answer switch 111 is re- 65 stored to normal, the above-traced operating circuit for the relay R520 is interrupted to cause 70 this relay and the relay R540 to restore in the order named, and the series circuit for energizing the signal lamp 126 and the relay R270 is inter- 75 rupted causing the last-mentioned relay to re- 80 store. When R270 restores, it removes ground from the amplifier start conductor C294, thereby 85 to render the signal amplifier inactive and to open a point in the operating circuit for R670, 90 and opens, at RA271, a point in the above-traced bridging path between the conductors C327 and C328 of the line 323. Following the restoration 95 of the three relays R520, R540 and R270, the auxiliary transmitting and receiving means are 100 entirely disconnected from the line 323. If desired, the telephone receiver embodied in the substation apparatus 600 may be retained off its sup- 105 porting element when the answer switch 111 is restored to normal. In such case the substation 110

apparatus is directly connected to the line 323 when the relay R670 restores in response to the removal of ground potential from the start conductor C294, and may be used in the usual manner.

As pointed out previously, to initiate a call at the special substation intended for a substation connected to a line not directly accessible to the special switching means, such, for example, station B connected to the line 321, it is necessary to employ the dial operated calling device conventionally included in the substation apparatus 600. Such a call is initiated in the usual manner by removing the hand set embodied in the apparatus 600 from its supporting cradle to cause a bridging path to be placed across the line conductors C321 and C322 of the line 323. As a result of the completion of this path, one of the non-numerical switches included in the switching equipment 320 responds by extending the calling loop circuit through to one of the numerical impulse responsive switches of the exchange, whereby the seized switch is conditioned to respond to impulses transmitted thereto by way of the calling line 323. When the calling loop circuit is completed, the relays R680 and R690 sequentially operate, but without effect since the conductors C294 and C694 are not grounded and accordingly the relay R670 is not energized. The seized impulse responsive switch and one or more additional impulse responsive switches successively respond to the impulses of successive digits dialed at the calling substation by extending the connection to the called line 321 in the usual manner. If, following the dialing operation, the selected called line is found busy, busy tone is returned over the calling loop and is reproduced by the receiver included in the apparatus 600 to give an audible indication that the desired connection cannot be obtained. On the other hand, if the selected called line is idle, ringing current is projected thereover to actuate the signal device at the called substation and ring-back tone is conducted back over the calling loop circuit to indicate to the calling party that the called substation is being rung. When the call is answered at the called substation, the desired conversational connection is completed in the usual manner.

Following the completion of a connection to the substation B in the manner just described, the auxiliary transmitting and receiving means comprising the transmitter microphone 135 and loud speaker 136 may be substituted for the transmitter and receiver embodied in the hand set for use in transmitting and reproducing signal currents. Such substitution is accomplished by operating the answer switch 111 to its off-normal position to cause the operation of the three relays R270, R520 and R540, and then replacing the hand set of the apparatus 600 upon its supporting element. The three relays noted operate in the exact sequence and perform the same functions as are described in detail in a preceding portion of the specification. In addition, the relay R270, upon operating, completes an alternative circuit for energizing the relay R670, this circuit extending from ground at RA272 by way of RA274, C694, RA692, RA673 and the lower winding of R670 to battery. When this circuit is completed the relay R670 operates to complete the holding circuit for R680 and R670, and to perform the various switching functions previously explained. When the hand set of the substation apparatus 600 is replaced upon its sup-

porting element, the holding circuit for the two relays R670 and R680 is interrupted, whereby the three relays R680, R690 and R670 are caused sequentially to restore in the order named. The relay R670, upon restoring, connects the line conductors C575 and C576 to the line terminals 643 and 644 and opens, at RA672, the path short-circuiting the transformer winding 629. Thus, the auxiliary transmitting and receiving apparatus is operatively connected to the line 323 over a 10 channel including the link line C575, C576, the link line C296, C297, and the transformer 300.

The purpose of first operating the answer switch 111 and then replacing the hand set of the apparatus 600 upon its supporting element is to prevent the established automatic switch train from being prematurely released. Thus, if the hand set is replaced upon its supporting element before the answer switch 111 is operated, the loop circuit extending to the operated switch train forming a part of the switching equipment 320 is interrupted. If the last numerical switch of the train, namely, the connector switch is of the "calling party release" type, the established switch train will release during the interval when the calling loop circuit is open and preceding operation of the answer switch 111. When, however, the answer switch 111 is operated prior to replacement of the hand set upon its supporting element, the relay R270 completes, at RA271, a 30 multiple loop circuit which precludes the release of the operated switch train.

It will be appreciated that the regular substation transmitter and receiver may be substituted at will for the transmitting microphone 135 and 35 the loud speaker 136 by removing the hand set or receiver from its supporting hook or replacing the same thereon, the three relays R670, R680 and R690 cooperating to effect the transfer in the exact manner previously described.

As indicated in the introductory portion of the specification, a calling party at the executive substation may utilize the special substation apparatus to initiate a direct call to one of the subordinate lines during the course of a conversation over an established connection to another of the lines extending to the exchange housing the automatic switching equipment 320. If the ensuing conversation is being held over a connection utilizing the regular substation transmitter and receiver embodied in the substation apparatus 600, the second call to the subordinate line may be initiated in the exact manner described above. For example, if the calling party is using the regular substation apparatus 600 to 55 converse over an established connection extending to the substation B and desires to secure information from the subordinate having an office in which the substation A is located, the direct call to the substation A is initiated by operating 60 the calling switch 100 to the lower off-normal position in the manner described above. The coding relays R200, R210 and R220, the common equipment 415 and the rotary switch 310 respond to the operation of the switch 100 to its off-normal position by performing the previously described functions, whereby a talking connection including the loud speaker 136 and the transmitter microphone 135 is established between the executive substation and the substation A. As 70 pointed out previously, one of the functions of the relay R450 is that of impressing ground potential upon the amplifier start conductor C294 thereby to condition the amplifier for operation and to prepare one of the operating circuits for 75

the relay R670. Since, however, the relays R680 and R690 are fully operated when the relay R450 operates, this operating circuit for the relay R670 is not completed, it being held open at the operated armature RA692. Thus, so long as the hand set is not replaced upon its supporting element the transmitter and receiver thereof are connected to the line 323 for communication thereover. Also, the auxiliary transmitting and receiving means are operatively connected for use in communicating over the established direct line connection. After the two connections have been established if the hand set is replaced upon its supporting element and is then removed therefrom, the relay R670 is caused to operate to disconnect the auxiliary transmitting and receiving apparatus from the direct line connection, to disconnect the substation apparatus from the line 323 and to connect this apparatus for use in communicating over the established direct line connection. More particularly, when the hand set is replaced upon its supporting element, the calling loop circuit is interrupted causing the two relays R680 and R690 sequentially to restore. These relays reoperate sequentially when the hand set is thereafter removed from its supporting element, the relay R690 first closing the "X" contacts associated with RA693 to complete the previously traced operating circuit for the relay R670. Thus, the relay R670 is caused to reoperate to effect the above-described transfer operation.

If, with the two connections established it is desired to connect the hand set to the direct line connection without releasing the first connection, namely, that extending by way of certain of the automatic switches of the switching equipment 320, the answer switch 111 and the transfer switch 110 are sequentially operated to their off-normal positions. When the answer switch 111 is operated the relays R270 and R520 sequentially operate and the relay R540 restores, all in the manner previously explained. The relay R270 completes, at RA271, the above-traced multiple calling loop circuit, thereby to prevent the release of the operated switches in the equipment 320, and completes, at RA272 and RA274, the above-traced alternative circuit for energizing the lower winding of the relay R670. The relay R670 now operates to complete the previously traced holding circuit for itself and the relay R680. With the three relays R270, R520 and R670 operated the substation apparatus is operatively connected by way of the link line C575, C576, the link line C296, C297 and the transformer 301 to the line 323. When the transfer switch 110 is operated following operation of the answer switch 111, the relay R520 restores to disconnect the substation apparatus from the line 323 and to connect this apparatus for use in communicating over the established direct line connection. Obviously, by operating the transfer switch 110 between its two positions the substation apparatus 600 may be transferred from one connection to the other at will. Also, by removing the hand set of the apparatus 600 from its supporting element and replacing the hand set upon its supporting element the hand set and the auxiliary transmitting and receiving means may be interchangeably connected to either of the two established connections. The switching apparatus is released in the manner set forth above when the operated calling switch 100, the answer switch 111 and the transfer switch 110 are restored to normal.

If the loud speaker 136 and the transmitter 135 are being used as the receiving and transmitting means in an established connection extending to the substation B, for example, and it is desired to use the special substation apparatus to initiate a call to one of the subordinate lines, as, for example, the line 322, directly accessible to the special substation equipment, it is necessary to operate the calling switch 100 to the off-normal position corresponding to the line 322 and following this, to operate the transfer switch 110 to its off-normal position. When the calling switch 100 is operated to the off-normal position corresponding to the line 322, the apparatus illustrated in Figs. 2, 3, 4 and 5 operates to cause a connection to be extended to the line 322 in the exact manner previously described. In this regard it will be recalled that the three relays R270, R520 and R540 are operated. Hence, the amplifier comprising the vacuum tube 620 is conditioned for operation and the line conductors C575 and C576 incoming to the anti-side-tone impedance network 630 are connected through to the repeating coil 300. The operated condition of the three relays R270, R520 and R540 in no way interferes with the operation of the other relays included in the common control apparatus 415 to cause the connection to the desired subordinate line 322 to be established. When the transfer switch 110 is operated to its off-normal position, following operation of the calling switch 100 to the off-normal position corresponding to the called subordinate line 322, the operating circuit for the relay R520 is interrupted at the springs 124, causing this relay to restore. When the relay R520 falls back, it disconnects the line conductors C575 and C576 from across the terminals of the transformer winding 301 and connects these line conductors to the respective terminals of the transformer winding 501, thereby operatively to include the auxiliary transmitting and receiving means comprising the loud speaker 136 and the transmitter microphone 135 in the established connection extending to the called subordinate line 322. The relay R520, upon restoring, also disconnects the conductor C574 from the conductor C573 and connects it to the conductor C572, thus substituting the line balancing circuit comprising the inductance element 631 and the resistor 632 for the balancing circuit comprising the inductance element 631' and the resistor 632' in the anti-side-tone impedance network 630. With the relay R520 in its restored position, the original circuit for supplying energizing current to the microphone 135 and for holding R540 operated, is interrupted at RA528'. At this time, however, the back bridge relay R510 is in its operated position so that a multiple circuit extending from ground at RA511 and by way of RC513 and RA532 is completed for maintaining R540 operated and for supplying energizing current to the microphone 135.

It will be noted that to effect the transfer operation just described the transfer switch 110 is operated to its off-normal position without restoring the answer switch 111 to its normal position. So long as the last-mentioned switch is retained in its off-normal position, the above-traced circuit by way of which the relay R270 is energized is held completed and, so long as R270 is energized and remains in its operated position, the loop circuit extending to the substation B and including the line 322 is maintained completed at RA271. After the two con-

nections extending, respectively, to the substations A and B are established, the party at the executive substation may, by operating the transfer key between its normal and off-normal positions, converse over either of the two connections at will. Thus, if the party at the executive substation, after conversing with the called party at the substation A, desires to again converse with the party at the substation B, he may do so by returning the transfer switch 110 to its normal position to recomplete the above-traced operating circuit for R520. It will be apparent, in view of the foregoing description, that when R520 reoperates it substitutes the balancing circuit comprising the inductance element 631' and the resistor 632' for the balancing circuit 631, 632 in the anti-side-tone impedance network, disconnects the line conductors C575 and C576 from the transformer winding 501, and reconnects the line conductors C575 and C576 to the terminals of the repeating transformer winding 301. It will also be apparent that the relay R670 may be controlled by removal of the hand set embodied in the apparatus 600 from its supporting element, selectively to connect this hand set and the auxiliary transmitting and receiving means for use in communicating over either of the two established connections.

In order to release the two established connections, it is only necessary to restore the operated switches 100 and 111 to normal and to replace the hand set upon its supporting element. When the switch 100 is returned to its normal position, the three operated coding relays R200, R210 and R220 are caused to restore, together with the start relay R450. Following the restoration of these four relays, the remaining operated relays embodied in the common control apparatus 415 are caused sequentially to restore in the manner described in detail in a preceding portion of the specification. Also, when the answer switch 111 is returned to its normal position, the operated ones of the relays R520, R540, R270, R670, R680 and R690 are deenergized and restore in the manner described previously.

With the arrangement illustrated, if a party at the executive substation is conversing over an established direct line connection routed by way of the switch 310 and desires information from another party having a line terminating at the exchange housing the switching equipment 320, it is necessary to release the established connection and then initiate the second call. This is true for the reason that the start relay R450 is always operated as an incident to the completion of a direct line connection. With this relay operated, ground potential is present upon the amplifier start conductor C294. Hence, the hand set of the apparatus 600 cannot be removed from its supporting element without causing the operation of the transfer relay R670. Obviously, with the relay R690 operated switch control pulses cannot be transmitted from the calling device embodied in the apparatus 600 over the line 323 to the automatic switching equipment 320.

In order to obviate the difficulty mentioned in the preceding paragraph, a second calling device 350 which is connected to the line 323 in the manner shown by the dotted line connections may be provided. More particularly, the strap between the terminals 355 and 356 is removed, these terminals are respectively connected to the pulsing springs 351 and 352, and the shunt spring 353 is connected to the line conductor C328. With

the calling device 350 connected to the line 323 in the manner just described, operation of the relay R270 in response to operation of the answer switch 111 effects the completion of a calling loop circuit by way of the line 323 which includes the pulsing springs 351 and 352. This loop circuit is interrupted at the indicated pulsing springs one or more times during each operation of the calling device. Also, each time the dial of the calling device is moved off-normal the shunt springs 353 and 354 are moved into engagement in the usual manner to complete an obvious path for shunting the transformer windings 303 and 304 and the resistor 306 out of the pulsing circuit. From the foregoing explanation it will be apparent that after a connection has been routed through the automatic switching equipment to a called substation in response to operation of the calling device 350, either the hand set embodied in the substation apparatus 600 or the auxiliary transmitting and receiving means may be used in communicating over the connection. Also, either set of transmitting and receiving apparatus may be transferred from the connection extending through the automatic switching equipment 320 to a direct line connection routed by way of the switch 310 at will and in the manner previously explained by operating the transfer switch 110 between its two positions.

While there have been described what are at present considered to be the preferred embodiments of the invention, it will be understood that various modifications may be made therein, and it is intended to cover in the appended claims all such modifications as fall within the true spirit and scope of the invention.

What is claimed is:

1. A telephone substation adapted to be connected to either of two telephone lines for communication thereover and comprising, in combination, a transmitter and a receiver normally connected to one of said lines, a relay, a circuit including said one line for energizing said relay, and means responsive to operation of said relay for disconnecting said transmitter and receiver from said one line and for connecting said transmitter and receiver for use in communicating over the other of said lines. 40

2. A telephone substation adapted to be connected to either of two telephone lines for communication thereover and comprising, in combination, a transmitter and a receiver normally connected to one of said lines, a relay comprising a winding serially included in said one line and adapted to be energized in response to the completion of a loop circuit including said one line, and means responsive to operation of said relay for disconnecting said transmitter and receiver from said one line and for connecting said transmitter and receiver for use in communicating over the other of said lines. 50

3. A telephone substation adapted to be connected to either of two telephone lines for communication thereover and comprising, in combination, a transmitter and a receiver normally adapted to be used in communicating over one of said lines, a first relay comprising a winding serially included in said one line and adapted to be energized in response to the completion of a loop circuit including said one line, a second relay operative to connect said transmitter and receiver for use in communicating over the other of said lines, said second relay including a winding, a circuit for energizing the winding of said 60

second relay, means responsive to operation of said first relay for completing said last mentioned circuit, and a holding circuit serially including the windings of said relays, said holding circuit being completed in response to the operation of said second relay.

4. A telephone substation adapted to be connected to either of two telephone lines for communication thereover and comprising, in combination, a transmitter and a receiver normally adapted to be used in communicating over one of said lines, a first relay comprising a winding serially included in said one line and adapted to be energized in response to the completion of a loop circuit including said one line, a second relay including a pair of windings, means responsive to operation of said first relay for energizing one of the windings of said second relay, thereby to cause the partial operation of said second relay, a second energizing circuit for said second relay, said second circuit serially including the windings of said relays and being completed in response to the partial operation of said second relay, thereby to cause said second relay to complete its operation, and means responsive to the last-mentioned operation of said second relay for connecting said transmitter and receiver for use in communicating over the other of said lines.

5. A telephone substation adapted to be connected to either of two telephone lines for communication thereover and comprising, in combination, a transmitter and a receiver normally adapted to be used in communicating over one of said lines, auxiliary receiving means normally adapted to be used in communicating over the other of said lines, a first relay comprising a winding serially included in said one line and adapted to be energized in response to the completion of a loop circuit including said one line, a second relay including a pair of windings, means responsive to operation of said first relay for energizing one of the windings of said second relay, thereby to cause the partial operation of said second relay, means responsive to the partial operation of said second relay for rendering said auxiliary receiving means inoperative, a second energizing circuit for said second relay, said second circuit serially including the windings of said relays and being completed in response to the partial operation of said second relay, thereby to cause said second relay to complete its operation, and means responsive to the last-mentioned operation of said second relay for connecting said transmitter and receiver for use in communicating over said other line.

6. A telephone substation adapted to be connected to either of two telephone lines for communication thereover and comprising, in combination, a transmitter and a receiver normally connected to one of said lines, a supporting element for said receiver, a relay, a circuit including said one line for energizing said relay, means responsive to removal of said receiver from said supporting element for completing said circuit, and means responsive to operation of said relay for connecting said transmitter and receiver for disconnecting said transmitter and receiver from said one line and for use in communicating over the other of said lines.

7. A telephone substation adapted to be connected to either of two telephone lines for communication thereover and comprising, in combination, a transmitter and a receiver normally connected to one of said lines, a supporting ele-

ment for said receiver, a relay comprising a winding serially included in said one line and adapted to be energized in response to the completion of a loop circuit including said one line, means responsive to removal of said receiver from said supporting element for completing said loop circuit, and means responsive to operation of said relay for disconnecting said transmitter and receiver from said one line and for connecting said transmitter and receiver for use in communicating over the other of said lines.

8. A telephone substation adapted to be connected to either of two telephone lines for communication thereover and comprising, in combination, a transmitter and a receiver normally adapted to be used in communicating over one of said lines, a supporting element for said receiver, a first relay comprising a winding serially included in said one line and adapted to be energized in response to the completion of a loop circuit including said one line, means responsive to removal of said receiver from said supporting element for completing said loop circuit, a second relay including a winding, a circuit for energizing the winding of said second relay, means responsive to operation of said first relay for completing said last-mentioned circuit, means responsive to operation of said second relay for connecting said transmitter and receiver for use in communicating over said other line, and a holding circuit serially including the windings of said relays, said holding circuit being completed in response to operation of said second relay and being interrupted in response to replacement of said receiver upon said supporting element.

9. A telephone substation adapted to be connected to either of two telephone lines for communication thereover and comprising, in combination, a transmitter and a receiver normally adapted to be used in communicating over one of said lines, a supporting element for said receiver, a first relay comprising a winding serially included in said one line and adapted to be energized in response to the completion of a loop circuit including said one line, means responsive to removal of said receiver from said supporting element for completing said loop circuit, a second relay including a pair of windings, means responsive to operation of said first relay for energizing one of the windings of said second relay, thereby to cause the partial operation of said second relay, a second energizing circuit for said second relay, said second circuit serially including the windings of said relays and being completed in response to the partial operation of said second relay, thereby to cause said second relay to complete its operation, and means responsive to the last-mentioned operation of said second relay for connecting said transmitter and receiver for use in communicating over the other of said lines.

10. A telephone substation adapted to be connected to either of two telephone lines for communication thereover and comprising, in combination, a transmitter and a receiver normally adapted to be used in communicating over one of said lines, a supporting element for said receiver, auxiliary receiving means normally adapted to be used in communicating over the other of said lines, a first relay comprising a winding serially included in said one line and adapted to be energized in response to the completion of a loop circuit including said one line, a switch operative

to complete said loop circuit in response to removal of said receiver from said supporting element, a second relay including a pair of windings, means responsive to operation of said first relay for energizing one of the windings of said second relay, thereby to cause the partial operation of said second relay, means responsive to the partial operation of said second relay for rendering said auxiliary receiving means inoperative, a second 5 energizing circuit for said second relay, said second circuit serially including the windings of said relays and being completed in response to the partial operation of said second relay, thereby to cause said second relay to complete its operation 10 and means responsive to the last-mentioned operation of said second relay for connecting said transmitter and receiver for use in communicating over said other line, said switch being operative to interrupt said second circuit when said receiver is replaced upon said supporting element. 15

11. A telephone substation adapted to be connected to either of two telephone lines for communication thereover and comprising, in combination, a transmitter and a receiver normally 20 adapted to be used in communicating over one of said lines, auxiliary receiving means normally adapted to be used in communicating over the other of said lines, switching means for connecting said auxiliary receiving means for use in 25 communicating over said one line, a first relay comprising a winding adapted to be energized in response to the completion of a loop circuit including said one line, a second relay, a circuit jointly controlled by said switching means and said first relay for energizing said second relay, and means responsive to the operation of said second relay for connecting said transmitter and receiver for use in communicating over said other line. 30

12. A telephone substation adapted to be connected to either of two telephone lines for communication thereover and comprising, in combination, a transmitter and a receiver normally 35 adapted to be used in communicating over one of said lines, auxiliary receiving means normally adapted to be used in communicating over the other of said lines, switching means for connecting said auxiliary receiving means for use in communicating over said one line, a first relay comprising a winding adapted to be energized in response to the completion of a loop circuit including said one line, a second relay, a circuit jointly controlled by said switching means and said first relay for energizing said second relay, and means responsive to the operation of said second relay for connecting said transmitter and receiver for use in communicating over said other line, and an alternative channel jointly controlled by said switching means and said second relay for connecting said transmitter and receiver for use in communicating over said one line. 40

13. A telephone substation adapted to be connected to either of two telephone lines for communication thereover and comprising, in combination, a transmitter and a receiver normally 45 adapted to be used in communicating over one of said lines, auxiliary receiving means normally adapted to be used in communicating over the other of said lines, switching means for connecting said auxiliary receiving means for use in communicating over said one line, a first relay comprising a winding adapted to be energized in response to the completion of a loop circuit including said one line, a second relay, a circuit jointly controlled by said switching means and said first

relay for energizing said second relay, means responsive to operation of said second relay for connecting said transmitter and receiver for use in communicating over said other line, and means also responsive to operation of said second relay 5 for rendering said auxiliary receiving means inoperative.

14. A telephone substation adapted to be connected to either of two telephone lines for communication thereover and comprising, in combination, a transmitter and a receiver normally adapted to be used in communicating over one of said lines, auxiliary receiving means normally adapted to be used in communicating over the other of said lines, switching means for connecting said auxiliary receiving means for use in communicating over said one line, a first relay comprising a winding adapted to be energized in response to the completion of a loop circuit including said one line, a second relay, a circuit 10 jointly controlled by said switching means and said first relay for energizing said second relay, means responsive to operation of said second relay for rendering said auxiliary receiving means inoperative and for connecting said transmitter 15 and receiver for use in communicating over said other line, and an alternative channel jointly controlled by said switching means and said second relay for connecting said transmitter and receiver for use in communicating over said one line. 20

15. A telephone substation adapted to be connected to either of two telephone lines for communication thereover and comprising, in combination, a transmitter and a receiver normally 25 adapted to be used in communicating over one of said lines, a supporting element for said receiver, auxiliary receiving means normally adapted to be used in communicating over the other of said lines, switching means for connecting said auxiliary receiving means for use in communicating over said one line, a first relay comprising a winding adapted to be energized in response to the completion of a loop circuit including said one line, a switch operative to complete said loop 30 circuit in response to removal of said receiver from said supporting element, a second relay, a circuit jointly controlled by said switching means and said first relay for energizing said second relay, a holding circuit for said relays, said 35 holding circuit being completed in response to operation of said second relay and being interrupted in response to replacement of said receiver upon said supporting element, and means responsive to operation of said second relay for 40 connecting said transmitter and receiver for use in communicating over said other line. 45

16. A telephone substation adapted to be connected to either of two telephone lines for communication thereover and comprising, in combination, a transmitter and a receiver normally 50 adapted to be used in communicating over one of said lines, a supporting element for said receiver, auxiliary receiving means normally adapted to be used in communicating over the other of said lines, switching means for connecting said auxiliary receiving means for use in communicating over said one line, a first relay comprising a winding adapted to be energized in response to the completion of a loop circuit including said 55 one line, a switch operative to complete said loop circuit in response to removal of said receiver from said supporting element, a second relay, a circuit jointly controlled by said switching means and said first relay for energizing said 60

second relay, a holding circuit for said relays, said holding circuit being completed in response to operation of said second relay and being interrupted in response to replacement of said receiver upon said supporting element, means responsive to operation of said second relay for connecting said transmitter and receiver for use in communicating over said other line, and an alternative channel jointly controlled by said switching 5 means and said second relay for connecting said transmitter and receiver for use in communicating over said one line.

17. In a telephone system, a plurality of lines, a telephone substation including a transmitter 10 and a receiver, switching equipment for setting up a first connection between said substation and one of said lines, a relay comprising a winding serially included in said connection and energized thereover when said connection is completed, additional switching means controllable 15 only from said substation for setting up a second connection between said substation and another of said lines without releasing said first connection, and means jointly controlled by said relay 20 and said additional switching means for connecting said transmitter and receiver for use in communicating over said second connection.

18. In a telephone system, a plurality of lines, a telephone substation including a transmitter 25 and a receiver, switching equipment for setting up a first connection between said substation and one of said lines, a relay comprising a winding serially included in said connection and energized thereover when said connection is completed, additional switching means controllable 30 only from said substation for setting up a second connection between said substation and another of said lines without releasing said first connection, means jointly controlled by said relay and 35 said additional switching means for connecting said transmitter and receiver for use in communicating over said second connection, and switching means for reconnecting said transmitter and receiver for use in communicating over 40 said first connection.

19. In a telephone system, a plurality of lines, a telephone substation including a transmitter and a receiver, switching equipment for setting up a first connection between said substation and 45 one of said lines, a relay comprising a winding serially included in said connection and energized thereover when said connection is completed, additional switching means controllable only from said substation for setting up a second connection between said substation and another of said lines without releasing said first connection, means jointly controlled by said relay and 50 said additional switching means for connecting said transmitter and receiver for use in communicating over said second connection, switching apparatus, and an alternative channel controlled by said switching apparatus for reconnecting said transmitter and receiver for use in communicating over said first connection.

65 20. In a telephone system, a plurality of lines, a telephone substation including a transmitter and a receiver, switching equipment for setting up a first connection between said substation and one of said lines, a relay comprising a winding 60 serially included in said connection and energized thereover when said connection is completed, additional switching means controllable only from said substation for setting up a second connection between said substation and another of said lines without releasing said first connection, said auxiliary receiving means normally 65 being connected and arranged to be used in communicating over a connection routed by way of said switching means, a relay comprising a winding serially included in said connection and energized thereover when said connection is completed, additional switching means controllable 70 only from said substation for setting up a second connection between said substation and another of said lines without releasing said first connection, said auxiliary receiving means normally being connected and arranged to be used in com-

75 connection, a second relay, a circuit jointly controlled by said first relay and said additional switching means for energizing said second relay, and means responsive to operation of said second relay for connecting said transmitter and receiver for use in communicating over said second connection.

21. In a telephone system, a plurality of lines, a telephone substation including a transmitter and a receiver, switching equipment for setting up a first connection between said substation and one of said lines, a relay comprising a winding serially included in said connection and energized thereover when said connection is completed, additional switching means controllable 15 only from said substation for setting up a second connection between said substation and another of said lines without releasing said first connection, a second relay, a circuit jointly controlled by said first relay and said additional 20 switching means for energizing said second relay, means responsive to operation of said second relay for connecting said transmitter and receiver for use in communicating over said second connection, switching apparatus, and an alternative 25 channel jointly controlled by said second relay and said switching apparatus for connecting said transmitter and receiver for use in communicating over said first connection.

22. In a telephone system, a plurality of lines, a telephone substation including a transmitter and a receiver, auxiliary receiving means at said substation, switching equipment for setting up a first connection between said substation and one of said lines, said transmitter and receiver 30 being arranged normally to be used in communicating over a connection routed by way of said switching means, a relay comprising a winding serially included in said connection and energized thereover when said connection is completed, additional switching means controllable 35 only from said substation for setting up a second connection between said substation and another of said lines without releasing said first connection, said auxiliary receiving means normally being connected and arranged to be used in communicating over a connection routed by way of said additional switching means, switching apparatus for connecting said auxiliary receiving means for use in communicating over said first connection, means jointly controlled by said relay and said additional switching means for connecting said transmitter and receiver for use in 40 communicating over said second connection, and means included in said switching apparatus for reconnecting said transmitter and receiver for use in communicating over said first connection.

50 23. In a telephone system, a plurality of lines, a telephone substation including a transmitter and a receiver, auxiliary receiving means at said substation, switching equipment for setting up a first connection between said substation and one of said lines, said transmitter and receiver being arranged normally to be used in communicating over a connection routed by way of said switching means, a relay comprising a winding serially included in said connection and energized thereover when said connection is completed, additional switching means controllable 55 only from said substation for setting up a second connection between said substation and another of said lines without releasing said first connection, said auxiliary receiving means normally being connected and arranged to be used in com-

municating over a connection routed by way of 5
said additional switching means, switching apparatus for connecting said auxiliary receiving means for use in communicating over said first connection, means jointly controlled by said relay and said additional switching means for connecting said transmitter and receiver for use in communicating over said second connection, and an alternative channel jointly controlled by 10
said relay and said switching apparatus for connecting said transmitter and receiver for use in communicating over said first connection.

24. In a telephone system, a substation including 15
a transmitter and receiver, a plurality of lines including one line extending to said substation, automatic switching equipment having access to said lines and operative to set up a first connection between said one line and a second of said lines, a relay comprising a winding serially 20
included in said connection and energized thereover when said connection is completed, additional switching means controllable only from said substation for setting up a second connection between said substation and another of said 25
lines without releasing said first connection, means jointly controlled by said relay and said additional switching means for connecting said transmitter and receiver for use in communicating over said second connection, switching 30
means for reconnecting said transmitter and receiver for use in communicating over said first connection, and means controlled by a portion of said last-named switching means for busying said one line to said automatic switching 35
equipment when no connection involving said substation and routed by way of said automatic switching equipment is established.

25. In a telephone system, a substation including 40
a transmitter and receiver, a plurality of lines including one line extending to said substation, automatic switching equipment having access to said lines and operative to set up a first connection between said one line and a second of said lines, a relay comprising a winding 45
serially included in said connection and energized thereover when said connection is completed, additional switching means controllable only from said substation for setting up a second connection between said substation and another 50
of said lines without releasing said first connection, means jointly controlled by said relay and said additional switching means for connecting said transmitter and receiver for use in communicating over said second connection, an answer 55
switch and a transfer switch, means responsive to operation of said answer switch for reconnecting said transmitter and receiver for use in communicating over said first connection, means operative when said answer switch is operated and in response to operation of said transfer switch for reconnecting said transmitter and receiver for use in communicating over said second connection, and means jointly controlled by 60
said transfer and answer switches for busying said one line to said automatic switching equipment when no connection involving said substation and routed by way of said automatic switching equipment is established.

26. In a telephone system, a substation including 65
a transmitter and receiver, a plurality of lines including one line extending to said substation, automatic switching equipment having access to said lines and operative to set up a first connection between said one line and a second of 70
said lines, a relay comprising a winding serially

included in said connection and energized thereover when said connection is completed, additional switching means controllable only from said substation for setting up a second connection between said substation and another of said 5
lines without releasing said first connection, means jointly controlled by said relay and said additional switching means for connecting said transmitter and receiver for use in communicating over said second connection, said one line 10
including a private conductor extending to said automatic switching equipment, an answer switch and a transfer switch at said substation, means responsive to operation of said answer switch for reconnecting said transmitter and 15
receiver for use in communicating over said first connection, means operative when said answer switch is operated and in response to operation of said transfer switch for reconnecting said transmitter and receiver for use in communicating over said second connection, and a path 20
jointly controlled by said answer and transfer switches for impressing a line busying potential upon said private conductor.

27. In a telephone system, a substation including 25
a transmitter and receiver, a plurality of lines including one line extending to said substation, automatic switching equipment having access to said lines and operative to set up a first connection between said one line and a second of said lines, a relay comprising a winding 30
serially included in said connection and energized thereover when said connection is completed, additional switching means controllable only from said substation for setting up a second connection between said substation and another of said lines without releasing said first connection, means jointly controlled by said relay and said additional switching means for connecting said transmitter and receiver for use 35
in communicating over said second connection, said one line including a private conductor extending to said automatic switching equipment, an answer switch and a transfer switch at said substation, means responsive to operation of said 40
answer switch for reconnecting said transmitter and receiver for use in communicating over said first connection, means operative when said answer switch is operated and in response to operation of said transfer switch for reconnecting 45
said transmitter and receiver for use in communicating over said second connection, and a path completed only in response to operation of said transfer switch at a time when said answer switch is not operated for impressing a line busying potential upon said private conductor.

28. In a telephone system, a substation, a plurality of lines including one line extending to said substation, automatic switching equipment for setting up connections between said lines, additional switching equipment controllable only from said substation for setting up connections between said substation and said lines, and means controllable from said substation for busying said one line to said first-named automatic switching 60
equipment when no connection involving said substation and routed by way of said first-named automatic switching equipment is established.

29. In a telephone system, a substation, a plurality of lines including one line extending to said 70
substation, automatic switching equipment for setting up connections between said lines and including an automatic switch having contacts terminating the conductors of said one line, said one line including a private conductor, additional 75

- 5 automatic switching apparatus controllable only from said substation for setting up connections between said substation and said lines, and means at said substation for impressing a line busying potential upon said private conductor, thereby to prevent calls from being routed to said substation during intervals when connections involving said substation and said additional switching apparatus are established.
- 10 30. In a telephone system, a substation, a plurality of lines including one line extending to said substation, automatic switching equipment for setting up connections between said lines and including an automatic switch having contacts terminating the conductors of said one line, said one line including a private conductor, additional automatic switching apparatus controllable only from said substation for setting up connections

between said substation and said lines, a transmitter and a receiver at said substation, a transfer switch at said substation, means controlled by said transfer switch for selectively connecting said transmitter and receiver for use in communicating over a first connection established by way of said automatic switching equipment and a second connection established by way of said automatic switching apparatus, and a path controlled by said transfer switch for impressing a line busying potential upon said private conductor, thereby to prevent calls from being routed to said substation during intervals when connections involving said substation and said additional automatic switching apparatus are established. 5 10 15

ROSWELL H. HERRICK.

CERTIFICATE OF CORRECTION.

Patent No. 2,224,477.

December 10, 1940.

ROSWELL H. HERRICK.

It is hereby certified that error appears in the printed specification of the above numbered patent requiring correction as follows: Page 16, first column, lines 68 and 69, claim 6, strike out the words "disconnecting said transmitter and receiver from said one line and for" and insert the same after "for" first occurrence, in line 67, same claim; page 17, second column, line 71, claim 16, for "operative" read --operative--; page 19, second column, line 43, claim 27, after "equipment" insert a comma; and that the said Letters Patent should be read with this correction therein that the same may conform to the record of the case in the Patent Office.

Signed and sealed this 4th day of February, A. D. 1941.

Henry Van Arsdale,

(Seal)

Acting Commissioner of Patents.
